KONRAD EICHENAUER, OF NEU-ROSSEN, NEAR MERSEBURG, GERMANY, ASSIGNOR TO RHEINISCHE METALLWAAREN- UND MASCHINENFABRIK, OF DUSSELDORF-DERENDORF, GERMANY, A CORPORATION OF GERMANY

CALCULATING MACHINE FOR ALL SPECIES

Application filed July 21, 1927, Serial No. 207,426, and in Germany November 18, 1926.

In calculating machines for adding and subtracting purposes or for all species it is well known to electrically connect the keys of the machine with electromagnets in order to transfer the numeral values inserted in the machine and the result obtained in the machine simultaneously to a second machine, for instance a type-writer or a machine for punching holes in cards, so that the numeral values and results inserted and obtained respectively in the calculating machine visibly appear in the type-writer or in form of holes in the cards.

According to the present invention each key of the calculating machine is so constructed as to be able to perform a greater stroke than is necessary for inserting the corresponding numeral value into the machine. The arrangement is such that on depression of the key for inserting a numeral value into the machine the additional stroke is performed at the end of which the circuit is closed. After releasing the finger pressure upon the key, the latter is automatically moved back for a distance corresponding to the length of the additional stroke, whereby the circuit is opened. The value inserted into the machine remains, however, in the machine as the key is locked in the adjusted position by the device effecting the locking of the keys.

For obtaining the above mentioned effect the key may consist of two parts movable with regard to each other in the longitudinal direction. The amount of movement of the two parts with respect to each other is limited by suitable means, and a spring is inserted between the two parts of the key for holding them in the initial position which corresponds to one of the limiting positions. On depression of the key, first of all, the upper part is moved with regard to the lower part for the stroke allowed between the two parts and on further depression of the said key the upper part takes along with it the lower part against the action of the usual return spring, until this lower part comes into a position in which simultaneously or about simultaneously the contact members come into engagement, the numeral values

are inserted into the machine and the key is locked by the known locking rail.

The two relatively movable parts forming together the key may consist of a lower part forming the key shaft and an upper part surrounding the lower part and carrying the key button which parts may, against the pressure of a spring interposed between them, be moved with regard to each other for a stroke limited by a notch and a locking pin.

According to another construction, the key shaft carrying the key button is made of one piece. In the shaft of the key a notch, cooperating with the key locking rail and of a length including the additional stroke, is provided so that, after release of the finger pressure upon the key, the latter is moved backward by its return spring for a sufficient amount, to bring the contact pieces out of engagement, while, however, the key is held locked.

In the accompanying drawings the above mentioned modes of carrying out the invention are shown by way of example.

Fig. 1 is a diagrammatic general view of a calculating machine according to the invention,

Fig. 2 is a detail of a set of keys partly in section and

Figs. 3-5 are detail views in section of a key in three different positions.

As shown in the drawings a rail 1 is pivotally arranged below each transverse row of keys. The rail 1 is supported by pivots 2 and 3 mounted in rails 5 and 6 fixed to the side walls of the machine frame. Each rail 1 carries an insulated contact member 7 which cooperates with a contact member 8 insulated from and fixed to the machine frame the contact member 7 being normally held in the open position by springs 4. As will be seen from Fig. 1, the contact members 7 and 8 are connected by wires 9 and 10 respectively to electromagnets 11 arranged at a suitable machine part 12 of another machine, for instance a type-writer, a machine for punching holes in cards or the like. These electromagnets cause, if their circuits are closed by closing the contact members 7 and 8, operations in the secondary machine corre-

sponding to the operations performed in the primary machine.

In the construction shown in Fig. 2 each key shaft 13 is provided with an over-throw sleeve 14 carrying the key button 15 and capable of being shifted with regard to the key shaft 13. An interposed compression spring tends to hold both parts in the initial position or to bring them back into this position. The key shaft 13 is influenced in the usual manner by a return spring 17 and is in well known manner provided with a notch 18 in which on depression of the key the key locking rail 19 engages under the influence of the tension spring 20. The sleeve 14 is connected to the key shaft 13 by means of a screw 21 which may slide in a notch 22 provided in the key shaft and extending in the longitudinal direction of same and which serves for limiting the stroke of the sleeve 14. On pressure being applied to the key button 15 the lower end of the sleeve 14 comes into contact with the contact rail 1 causing the latter to swing about its pivots 2 and 3, so that, as shown in Fig. 2 at the right hand side, the contact member 7 comes into contact with the contact member 8. Simultaneously herewith the key locking rail 19 is moved under the action of spring 20 into the notch 18. As soon as the finger pressure upon the key button 15 is released, the latter, together with the sleeve 14, is moved back for a short distance. The amount of upward movement of the key button 15 and the sleeve 14 is determined by the length of the notch 22 and this upward movement is sufficient to bring the contacts 7 and 8 out of engagement. The key shaft 13 is held by the engagement of the locking rail 19 into the notch 18, so that the value inserted into the machine by this particular key remains in the machine. After the usual release only the key shaft 13 is again moved backward under the action of the spring 17.

In Figs. 3 to 5 a key consisting of one piece only is shown in the different positions which it can assume. The key shaft 13 in this construction carries directly the key button 15 the lower edge of which comes into contact with the rail 1 for the purpose of closing the contacts 7, 8. According to this modification the notch 18 is greater than the thickness of the locking rail 19. On exerting pressure upon the button 15 the several parts first are brought into the position shown in Fig. 5 in which the key locking rail 19 comes in the active position. Then the key may perform an additional stroke and comes in the position shown in Fig. 4 in which the contacts 7, 8 are closed by the lower edge of the button 15. After release of the finger pressure upon the key button, the key shaft is moved upward by the return spring 17 for the additional stroke, i. e. for the distance 65 by which the length of the notch 8 is greater

than the thickness of the locking rail. The several parts then assume the position shown in Fig. 5 in which the contacts 7, 8 are opened and the locking rail 19 engages the lower limiting face of the notch 18, so that, with the circuit broken and leaving the value in the machine, the key 15 is arrested.

The new machine works as follows:

If a multiplication, for instance 25.25 is to be carried out, the key 13 corresponding to the numeral value in the second row is depressed, whereby the rail 1 is rocked and the circuit is closed over the contacts 7, 8 and the appertaining electromagnet. Immediately after release of the finger pressure upon this key 13, the key button 15 (Fig. 2) is moved upward for the length of the notch 22, or the key shaft 13 (Figs. 3-5) is brought from the position shown in Fig. 4 to the position illustrated in Fig. 5, whereby the just closed circuit is opened, the inserted value, however, remains in the machine. The same cycle of operations is repeated when the key 13 in the first row of keys corresponding to the value 5 is depressed. In this manner the value 25 simultaneously with its insertion in the calculating machine is transmitted over the wires 9 and 10 and the appertaining electromagnets to the type-writer or the machine for punching holes in cards, so that this value 25 visibly appears in the type-writer or in form of holes in the cards. Then the multiplication is carried out in the known manner by depressing the multiplier values 2 and 5 in the multiplication-key-row 32 (Fig. 1), whereupon the result of the calculation appears in the windows 33 of the machine. To obtain this result, in the present case the value 625 in a second machine, type-writer, machine for punching holes in cards or the like, also, the keys 13 corresponding to the numeral value 6, 2, 5 are depressed in the order stated, so that the circuit is closed over the corresponding contacts 7, 8, wires 9, 10 and electromagnets, and the value 625 is written, represented in form of holes in a card or is fixed in any other manner. For controlling the calculation the corresponding division may be carried out, whereupon the keys are released so that the machine is ready for carrying out a further calculation.

In carrying out a division, for instance 625:25, the dividend 625 is first inserted by depression of the keys 13 corresponding to the numeral values 6, 2, 5. Hereby this dividend appears, in the manner explained above, also in the recording machine. By turning the handle or the like of the machine for one revolution the dividend is brought into the counting mechanism arranged below the windows 33. In known manner the keys are then released and the divisor is inserted by depression of the keys corresponding to the values 2 and 5 in the order stated. Hereby the divisor 25 also appears in the recording ma-

chine in a manner to be read off or to be sensed. The machine is now operated in the manner required for carrying out a division, whereupon the quotient 25 appears in the windows 34. The result of the calculation is transmitted electrically, in the manner explained above, by depressing the keys corresponding to the numeral values 2, 5 in the order stated.

10 What I claim is:

1. In a calculating machine as set forth, a normally open contact, a key capable of performing an additional stroke over that required for the setting up of the numeral 15 value in the machine, means provided on said key for closing said contact, said contact opening upon partial return of the key, and means for arresting the key after the said contact is opened but before the key is moved 20 back sufficiently to affect the insertion of the numeral values.

2. In a calculating machine having a keyboard composed of a plurality of numerical keys arranged in spaced horizontal rows and 25 in vertically aligned columns, the keys of each column increasing in numerical value from one end of the column to the other; a pair of normally open contacts forming part of an electric circuit and associated with each 30 horizontal row of keys, each of the keys of each row being arranged to close the contacts of such row simultaneously with the setting up of a numeral value in said machine by such key, and means for arresting the return 35 movement of any key at an intermediate point of its return travel, after said contacts have opened, to retain the set up numeral values in the machine.

3. In testimony whereof I have affixed my 40 signature.

KONRAD EICHENAUER.
